UNITED STATES PATENT OFFICE.

ROBERT H. HUMMERT, OF DAYTON, OHIO, ASSIGNOR TO THE S. H. THOMSON MANUFACTURING COMPANY, OF DAYTON, OHIO, A CORPORATION OF OHIO.

DESIGN FOR A RADIATOR CAP.

Application filed April 27, 1927. Serial No. 21,738. Term of patent 3½ years.

To all whom it may concern:

Be it known that I, ROBERT H. HUMMERT, a citizen of the United States, residing at Dayton, in the county of Montgomery and State of Ohio, have invented a new, original, and ornamental Design for a Radio Cap, of which the following is a specification, reference being had to the accompanying drawing, forming part hereof.

Figure 1 is a front elevational view, and Fig. 2 is a side elevational view, of a radiator cap, showing my new design.

I claim:

The ornamental design for a radiator cap, as shown.

ROBERT H. HUMMERT.
